UNITED STATES PATENT OFFICE.

EDMUND W. WOODRUFF, OF WASHINGTON, DISTRICT OF COLUMBIA.

DOCUMENT OR LETTER FILE.

SPECIFICATION forming part of Letters Patent No. 404,458, dated June 4, 1889.

Application filed March 11, 1889. Serial No. 302,787. (No model.)

To all whom it may concern:

Be it known that I, EDMUND W. WOODRUFF, a citizen of the United States, residing at Washington, in the District of Columbia, have 5 invented certain new and useful Improvements in Document and Letter Files; and I do declare the following to be a full, clear, and exact description of the invention, such as will enable others skilled in the art to which 10 it appertains to make and use the same.

While it is the practice in business to file away certain papers or documents in a folded condition, and also to store collections of such papers in envelopes or files, it is very desirable 15 for purposes both of economy of space and ready reference to preserve certain other papers (a common example of which is found in ordinary business-letters) in a flat or unfolded condition and in a properly-indexed arrangement. For these purposes two radically different styles of devices have heretofore been used, differing in external appearance and in 20 shape, and requiring a case or cabinet with differently-shaped compartments respectively adapted to the different styles of said 25 devices.

It is the object of my invention to provide 30 a means for filing papers which will be capable of holding the two styles of papers, (folded or unfolded,) and in which the two styles of holding devices shall be similar and uniform in external appearance and so analogous in 35 general shape and configuration that they may be arranged side by side or interchanged with each other, as convenience of arrangement, or situation in the cabinet, or the relative numbers of the two styles of holders may dictate.

It is a further object of my invention to 40 provide means for sustaining the paper-holding device, of whichever style, when the same is drawn out and while its contents are being examined.

To these ends my invention consists in the 45 parts and combinations of such hereinafter more particularly described and claimed.

In order to make my invention more clearly understood, I have shown in the accompanying drawings means for carrying the same 50 into practical effect.

In said drawings, Figure 1 is a perspective view of a cabinet and paper-holding devices

embodying my invention. Fig. 2 is perspective view of the holder, which may be termed the "letter-holder," for flat or unfolded papers, drawn out and opened. Fig. 3 is a perspective view of the same closed, provided with an index and filled with papers. Fig. 4 is a longitudinal section of this holder and of the adjacent parts of the case. Fig. 5 is 60 a transverse section of the same. Fig. 6 is a plan view of the devices or slides which sustain the letter-holder when the latter is drawn out. Fig. 7 is a similar view of a modified form of slide, more especially adapted for the 65 holder for folded papers, which may be termed the "document-holder." Fig. 8 is a longitudinal section illustrating the latter form of slide.

Referring to the drawings, A indicates a 70 case or cabinet provided with any desirable number of shelves *a* of convenient distance apart and adapted to receive the paper-holders. The holders which I employ and their sustaining devices are of such character that 75 they may be placed side by side upon the shelves *a* in immediate contiguity without intervening partitions. Economy of material and of space are thus secured. When shelves 80 of such length are employed that there might be a liability to bend or sag under a load of filled holders, I employ at intervals—say at every fourth holder, as shown in Fig. 1—a vertical support *a'*, which may be in the form of a partition running back the full depth of 85 the shelves or for a portion of such depth.

The cabinet may of course be constructed, if desired, with a separate space or compartment for each holder.

In the simplest form of the device the holders rest immediately upon the shelves without any slide or other device adapted to sustain them when drawn out upon the cabinet in front of their places, and when the contents of the holders are to be examined the latter will be removed bodily from their shelves and held in the hand or placed upon a convenient table, desk, or shelf. I will first describe this form of the holders without regard to the slide or sustaining device, which in some instances I prefer to use, and which is hereinafter more particularly referred to.

B indicates the holder for folded papers, which may be termed the "document-holder."

- It is made of a width suitable for the papers or file-envelopes which it is to contain—say four and three-quarters inches—and is provided with a follower or file-board *b*, operating in planes at right angles to the front. The direction of operation of such follower may be either vertical or horizontal, as is well known in this class of holders, the latter construction being shown in the drawings.
- o C indicates the holder for flat or unfolded papers—such as business-letters—which device may be termed, for the sake of distinction, the “letter-holder.” This holder is upright in position, and the papers within it rest upon their edges, being properly sustained between one of the sides *c* of the holder and a lateral file-board *c'*, which operates in planes parallel with the front *c²* of the device. At the side on which the follower is situated the holder is open, as shown. When closed, as shown on the top and bottom shelves in Fig. 1, the letter-holder presents the same external appearance (except for its label) as the document-holder, and is adapted to be readily interchanged with it. The whole filing apparatus, therefore, is uniform and regular in appearance, and the cabinet or case which forms a part of the same is equally uniform in construction, contributing much to simplicity and economy in manufacture. As convenience of arrangement may dictate, the different kinds of holder may be transferred from one part of the case to another—for instance, as they become filled and go out of current use—or different proportions in number of the document-holder and letter-holder may be accommodated from time to time in the same case as the course of business may render desirable.
  - o For convenience of examination the follower *c'* of the letter-holder is provided with a support *c³*, adapted to hold it in an outwardly-inclined position. (See Fig. 2.) When thus constructed the holder is particularly well adapted to receive a card-index *D*, having its lettered or indicating edge situated at the top of the holder. (See Fig. 3.) In order to facilitate the display of the dates and signatures of letters, the right side of the letter-holder is left open, and the follower *c'* and support *c³* arranged on that side. The holder may, however, be reversed in use, with its rear toward the person examining its contents. When intended to be so used the rear board *c⁴* may be cut away partly to give a better view of the interior of the holder and to facilitate the introduction of the hand in filing or removing letters. The direction of such cut is indicated by the dotted line *x*, (shown on the front board *c²* in Fig. 2, which front board may be considered, for the purpose of understanding this modification, as the rear board of the holder.)

The support *c³* for the file-board *c'* consists, by preference, of a lever mounted at its lower end and adapted to be moved from one side of the holder to the other in a T-groove *c⁵*,

formed in a plate fitted in the bottom of the holder. The construction and operation of this lever are well known and need not be here further set forth.

I will now proceed to describe the sustaining device or slide, which is adapted to support the holder, when drawn out, on the front of the case immediately in front of its space. While practically the same slide may be used with either type of holder, I prefer to modify its construction in certain details according to the particular form of holder with which it is to be used, with a view to secure more perfect and convenient working of the parts.

In Fig. 6 are shown in plan view two contiguous slides especially adapted for sustaining the letter-holder *C*. Referring to this figure, and also to Figs. 2, 4, and 5, *E* indicates the slide, preferably consisting of two side bars *e e*, a rear bar *e'*, and a front bar *e²*. The slide may be made in one piece or of several pieces secured together and of any suitable material. On their inner edges the bars *e* are provided with longitudinal rabbets *e³* and on their outer edges with similar rabbets *e⁴*.

F indicates a metal plate or button situated in the space between the bars *e*, secured to the upper side of the shelf *a*, and provided with an overhanging flange or head which fits in the rabbets *e³* of the side bars. This button is situated a short distance back from the front edge of the shelf, and, it will be seen, acts as a stop (by contact with the rear bar *e'*) to limit the forward movement of the slide, and also keeps the rear end of the slide from tipping up and maintains it in a horizontal position. The slides are caused to act as guides for each other by virtue of their contiguity. The letter-holder, when adapted to fit this form of slide, is provided upon its bottom at the edges with blocks *G* of such width as to fit the rabbets *e⁴*, and of such situation and length as to stop the forward movement of the letter-holder upon the slide when said holder is in the desired position. It is obvious that a mere inversion of the arrangement shown of the block or blocks *G* and the rabbet or rabbets *e⁴* may be used, the former being attached to the slide and the latter formed in the bottom of the holder. In the construction illustrated this position is that shown in Fig. 2, where the rear edge of the top of the letter-holder is just below and engaged by the edge of the shelf above. It will be seen that the holder is thus prevented from tipping up at its rear end and is maintained firmly in position suitable for the examination of papers.

It will be readily understood that the buttons *F* may be arranged at the edges of the slides and the blocks (or a single block) *G* situated in the central groove of the slide. When it is desired to remove the letter-holder bodily, it is simply necessary to draw it, with its slide, out to the full extent, and then

slightly raise the front of the holder till the forward ends of the blocks G are clear of the front bar e^2 , when there will be no obstacle to the entire removal of the holder. The 5 front edge of the bar e^2 forms or is provided with a bead or molding e^5 , which completely conceals the slide and gives a finish to the device.

In Fig. 7 is shown a modified form of slide 10 especially adapted in its details to the support of the document-holder B. As it is desired to have room for releasing and dropping back to an inclined position (see Fig. 1) the follower b, even though the holder be full, it 15 is preferred that the slide for this holder be adapted to sustain the latter when drawn out to a position entirely outside of the case A. Instead of relying upon the shelf above to assist in supporting this holder, therefore, the 20 block G, carried upon the bottom of the holder and fitting in the slide, is arranged centrally of the holder and slide, and is provided with lateral arms g, which extend for a short distance beneath the side bars e, fitting in rabbits e^6 , formed in the lower inner edges of the bars. Said arms g effectually maintain the 25 holder B in a horizontal position, even when drawn out to a point entirely beyond the case A.

30 At their rear ends the bars e are recessed on their inner sides, as shown at e^7 , to permit of the vertical passage of arms g when the holder is in the act of being removed bodily from the case and from its slide. To remove 35 the holder bodily, it is not necessary to operate its slide. If the holder be simply taken by its usual handle or ring r and tipped forward, the block G and arms g will pass upward through the central slot and recesses e^7 40 of the slide, and the holder will be freed from any connection with the case. It may be as readily replaced, these operations being as simple as if the holder were mounted directly upon the shelf without a slide. The block G 45 being situated centrally in this holder, the buttons F are arranged at the sides of and between the slides, as seen in Fig. 7. The slides are thus not contiguous, and as they will not serve as guides for one another I employ a 50 second button F' in line with button F, whereby the slide is prevented from having undue lateral play.

For the slide which comes next to the side of the case A or to the partition a' there is 55 provided a retaining finger or lug l, which is secured to said case or partition (see Fig. 7) and engages the rabbet in the edge of the slide.

By an examination of the form of slide 60 shown in Fig. 7 it will be seen that if the block G of the letter-holder be arranged centrally either this holder or the document-holder may be mounted on and used with this slide.

65 Instead of using the molding e^5 , the forward end of the slide may stop a little back of the face of the holder, and the front board of the

latter may extend down to the shelf, thus concealing the slide.

Having thus described my invention, what 70 I claim is—

1. The combination, with the upright letter-holder having an open side, of the lateral file-board or follower operating in planes parallel with the front of the case, substantially 75 as set forth.

2. The combination, with the upright letter-holder having the open side, of the lateral file-board or follower operating in planes parallel with the front of the case, and a card or 80 leaf index arranged within said holder with its leaves parallel with the sides of the holder and its marked or indicating edge situated at the top of said holder, substantially as set forth. 85

3. The combination, with the upright letter-holder having an open side, of the lateral file-board or follower operating in planes parallel with the front of the case, and a support engaging said follower and adapted to 90 support the same in an inclined position at the side of said holder, substantially as set forth.

4. The combination, with the upright letter-holder having an open side, of the lateral 95 file-board or follower operating in planes parallel with the front of the case, a support engaging said follower and adapted to support the same in an inclined position at the side of said holder, and a slide situated beneath the holder and adapted to sustain the same when drawn out, substantially as set forth. 100

5. The combination, with the cabinet or case A, of the document and letter holders of 105 uniform appearance, said document-holder being provided with a file-board or follower operating in planes at right angles to the front of the holder, and the upright letter-holder having an open side and a lateral follower 110 operating in planes parallel with the front of the holder, substantially as set forth.

6. As a means for filing papers, the combination, with the cabinet or case A, of the document-holder provided with a file-board 115 or follower operating in planes at right angles to the front of the holder, and the upright letter-holder having an open side and provided with a lateral follower operating in planes parallel with the front of the holder, 120 said holders being interchangeable, substantially as set forth.

7. The combination, with the case or cabinet, of a slide engaging the same and provided with a longitudinal slot or space, and 125 having a lateral recess e^7 at the rear end of the slot or space, whereby it is adapted to receive and sustain, when drawn out, either the document or letter holder, substantially as set forth. 130

8. The combination, with the case or cabinet having a shelf a and the holders, of the slides E, arranged contiguously to and adapted to keep each other in place on said shelf, and

retaining devices which hold said slides to the shelf, but permit their reciprocation, substantially as set forth.

9. The combination, with the shelf *a*, of the 5 slide *E*, having a longitudinal space with a lateral recess *e*, retaining devices which hold said slide to the shelf, but permit its reciprocation, and the holder provided with a stop which fits said space, and a lateral arm *g*,

adapted to engage the under side of the slide, to substantially as set forth.

In testimony whereof I affix my signature in the presence of two witnesses.

EDMUND W. WOODRUFF.
